CONNECTOR FOR FLANGED SHEETS ABUTTING ENDWISE

Otis W. Hovey, Pittsburgh, Pa., assignor to United States Steel Corporation, a corporation of New Jersey

Original application September 20, 1951, Serial No. 247,439. Divided and this application December 19, 1952, Serial No. 326,828

3 Claims. (Cl. 189—85)

This invention relates to a building construction and, in particular, to means for connecting the abutting ends of flanged sheathing plates.

This is a division from my abandoned application Serial No. 247,439 filed September 20, 1951, for "Eave and Gable-End Construction for Panel-Type Building."

The object of the invention is to provide a connector of the character indicated which is inexpensive to manufacture, easy to install and capable of maintaining a rigid joint indefinitely.

A complete understanding of the invention may be obtained from the following detailed description and explanation which refer to the accompanying drawings illustrating the present preferred embodiment. In the drawings,

Figure 1 is a partial elevation showing the connector joining the abutting ends of adjacent sheets or plates;

Figure 2 is a partial vertical section taken along the plane of line II—II of Figure 1; and

Figure 3 is a horizontal section taken along the plane of line III—III of Figure 1.

Referring in detail to the drawings, a wall of a building or other structure includes spaced struts or studs 48. The struts are sheathed with horizontally disposed elongated metal sheets 50 having overlapping flanges 51 bearing on the struts and secured thereto by screws 52.

My invention concerns a connector for uniting the abutting ends of adjacent sheets 50 at an end-to-end joint J between them. Clips or loops 54 of channel section are attached centrally to the back of each sheet ad-

2

jacent the end thereof which abuts an adjacent sheet. An E-shaped connector stamping or key 55 includes outer tongues 55a and a central tongue 55b having a flanged strip 56 welded thereto. With the abutting ends of adjacent sheets 50 alined, the connector is applied to the inner face of one sheet and pushed therewith until tongue 55b and strip 56 pass through both clips 54. Both tongues 55a and 55b and strip 56 will then overlap the joint and the flanges of strip 56 will be tightly wedged in the clips 54. The outer edges of tongues 55a are flanged to fit snugly against flanges 51 of the sheets 50 and the tip of the tongue 55b is bent inwardly to avoid interference with the end of the adjacent sheet.

Although I have disclosed herein but a preferred embodiment of my invention, I intend to cover as well any change or modification therein which may be made without departing from the spirit and scope of the invention.

I claim:

- 20 1. A structural joint comprising a pair of elongated metal sheets abutting end-to-end, both having a channel-section loop at the abutting ends thereof, and an E-shaped sheet-metal key in flatwise engagement with one of said sheets, the spaced upper and lower portions of said key extending across the plane between said ends outside of said loops and the mid-portion of the key extending through both said loops and fitting snugly therein.
- 25 2. The structure defined by claim 1 characterized by said mid-portion being of channel section.
3. The structure defined by claim 1 characterized by said sheets having bent-up flanges extending along their longitudinal edges, said upper and lower portions of said key having bent-up flanges fitting snugly within the flanges on the sheets.
